UNITED STATES PATENT OFFICE.

SACHARY WERSCHANSKY, OF NEW YORK, N. Y.

DESIGN FOR A SHAVING-BRUSH.

50,856.

Specification for Design.

Patented May 29, 1917.

Application filed November 18, 1916. Serial No. 132,227. Term of patent 3½ years.

To all whom it may concern:

Be it known that I, SACHARY WERSCHAN-SKY, a subject of the Russian Emperor, residing at New York, in the county of New York and State of New York, have invented a new, original, and ornamental Design for Shaving-Brushes, of which the following is a specification, reference being had to the accompanying drawing, forming part thereof.

The figure is an elevation of a shaving brush showing my new design.

I claim:

The ornamental design for a shaving brush as shown.

SACHARY WERSCHANSKY.
